UNITED STATES PATENT OFFICE

154,973

DESIGN FOR A HELICOPTER

Ralph P. Alex, Stratford, Conn., assignor to
United Aircraft Corporation, East Hartford,
Conn., a corporation of Delaware

Application May 20, 1947, Serial No. 139,165

Term of patent 7 years

(Cl. D71—1)

To all whom it may concern:

Be it known that I, Ralph P. Alex, a citizen of the United States, residing at 152 Norman Circle, Stratford, in the county of Fairfield and State of Connecticut, have invented a new, original, and ornamental Design for a Helicopter, of which the following is a specification, reference being had to the accompanying drawing, forming a part thereof.

Fig. 1 is a top plan view of a helicopter, showing my new design.

Fig. 2 is an elevational view showing one of the identical sides of the helicopter.

Fig. 3 is a front elevational view.

Fig. 4 is a top perspective view.

Fig. 5 is a top perspective view from a different angle.

The characteristic features of my design reside

in the portions shown by means of full lines in the drawing.

I claim:

The ornamental design for a helicopter, as shown and described.

RALPH P. ALEX.
